Primary Examiner — T Chase Nelson*(74) Attorney, Agent, or Firm* — HOGAN LOVELLS US LLP(57) **CLAIM**

The ornamental design for a shoe sole, as shown and described.

DESCRIPTION

FIG. 1 is a front left-side perspective view of a first embodiment of a shoe sole showing our new design; FIG. 2 is a front right-side perspective view thereof; FIG. 3 is a front perspective view thereof; FIG. 4 is a rear perspective view thereof; FIG. 5 is a left-side perspective view thereof; FIG. 6 is a right-side perspective view thereof; FIG. 7 is a top perspective view thereof; FIG. 8 is a bottom perspective view thereof; and, FIG. 9 is a partial, slightly enlarged rear left-side perspective view thereof.

FIGS. 1 through 9 depict a right shoe sole, and a second embodiment is a left shoe sole, which is a mirror image of the first embodiment.

The broken lines depict environmental structure and portions of shoe sole that form no part of the claimed design. The broken line frame around the FIG. 9 view shows the boundaries of the partial view, and also form no part of the claimed design.
